UNITED STATES PATENT OFFICE.

GEORGE L. HARRISON, OF EAST CLEVELAND, OHIO, ASSIGNOR TO THE CLEVELAND METAL PRODUCTS COMPANY, OF CLEVELAND, OHIO, A CORPORATION OF OHIO.

ARTICLE OF FURNITURE.

1,145,681.

Specification of Letters Patent.

Patented July 6, 1915.

Application filed July 14, 1913. Serial No. 778,877.

To all whom it may concern:

Be it known that I, GEORGE L. HARRISON, a citizen of the United States, residing at East Cleveland, in the county of Cuyahoga and State of Ohio, have invented a certain new and useful Improvement in Articles of Furniture, of which the following is a full, clear, and exact description, reference being had to the accompanying drawings.

10 This invention relates to improvements in the construction of kitchen or laboratory tables, bath room stands or stools, and other like articles of furniture; and its object is to provide a novel construction whereby 15 furniture, made in accordance therewith, is rendered sanitary; substantial and durable; and neat and attractive in appearance. I attain these objects by a construction illustrated in the accompanying drawings, 20 wherein I have shown, as an embodiment of my invention, a kitchen table.

As will be brought out clearly in the following description, the exposed parts of the table are made of sheet steel which is 25 heavily enameled and so formed and assembled as to offer no opportunity for the accumulation or retention of dust or dirt in any of its parts and permitting, also, of easy cleaning. I preferably employ wood as 30 means for stiffening and retaining in position certain of the parts of the table, whereby the table is made very strong, and these wooden parts are so protected by the enameled steel covering that they are subjected to no injury or deterioration from 35 exposure. Because of certain novel structural details which will be brought out hereinafter, the parts may be easily and rapidly assembled, thus materially reducing 40 the cost of production; and the particular way in which I form the table top to expedite the draining thereof, gives the table an artistic appearance.

In the drawings, Figure 1 represents a 45 front elevation of a table which is constructed in accordance with my invention; Fig. 2 is a plan thereof, a portion of the top covering being broken away to more clearly illustrate certain structural details; 50 Fig. 3 is a partial, central longitudinal section of the table; Fig. 4 is a transverse section, corresponding to the line 4—4 of Fig. 1 and looking in the direction of the arrows; Fig. 5 is a bottom plan view of the wooden 55 frame of the table top; Fig. 6 is a sectional

detail taken on the line 6—6 of Fig. 3 and looking in the direction of the arrows; while Figs. 7 to 10, inclusive, illustrate certain details of the table leg construction.

Proceeding with a detailed description of the invention wherein I will refer to the drawings by the use of reference characters, 60 1 represents a sheet metal covering for the table top which is bulged throughout its central portion and inclines therefrom in all directions toward its edges where it is finished in a bead 2 and a depending flange 3, the lower edge of the latter being turned inwardly at 4 to form therebetween and the bead 2 a channel. The sheet metal covering 65 1 is stiffened by the frame (which is designated, generally, by A and shown particularly in Fig. 5) which comprises a pair of longitudinal runners 5, transverse end members 6, and a central piece 7. The inner edges of the runners 5 are rabbeted as 70 are also the adjacent ends of the end members 6 and the central piece 7, the rabbeting of the runners 5 being complementary to the rabbeting of the transverse pieces 6 and 7. In placing the frame within the covering 75 1 the longitudinal runners 5 are first placed in position with their outer edges embraced by the channels formed by the bead 2, flange 3 and its lower turned edge 80 4. The end members 6 are then placed between the longitudinal runners 5 and are slid laterally until their outer edges are also embraced by the portions of the aforesaid channel which extend across the ends of the 85 covering 1. The central piece 7 is then placed in position where it is held by the strip 8 which extends longitudinally thereacross and is secured to the runners 5 by 90 screws 9.

As has been mentioned hereinbefore, the metal covering 1 is heavily enameled, and for the protection of such enamel against any undue shock (as the nature of such enamel is brittle and more or less fragile) 100 I prefer to insert between said covering and the wooden frame A, a layer of yielding material 10 such, for instance, as heavy felt paper. The yielding quality of the layer 10 will also assist in the clamping of the edges of the frame between the inturned edges 4 of the flange 3 and the bead 2. I 105 wish to call attention at this time, also, to the difference between the width of the inturned edge of the flange 3 and the width of 110

the bead 2, and state that, by so proportioning these parts, I retain the effective clamping action of the parts notwithstanding any irregularities which may exist in either the 5 edges of the frame, or the engaging parts of the covering 1 (unevenness of the latter parts being quite likely owing to the presence of the heavy enamel coating). In explanation of this fact, I will say that if the 10 bead were made the same width as the in-turned portion 4, or if it were dispensed with entirely, then the channel formed by the portion 4 and the opposed portion of the covering 1, would have a fixed width 15 and the edges of the frame A would have to be of corresponding thickness; and since the enameled parts are necessarily uneven, this would prove impractical. As it is, the members of the frame A act as levers of the 20 first class, and with their bearings upon the inner portion of the bead 2 as their fulcrum, they draw the in-turned edge 4 into the required position, the metal whereof the bead 2 is formed, springing sufficiently to permit of such action.

The skirt of the table comprises front and rear longitudinal portions 11 and 12 respectively, and end portions 13, and is formed, preferably, of one strip of metal, 30 the ends of which may be welded together at any desired point and it is provided about its upper edge with an outwardly turned horizontal flange 14. The general outline of the skirt of the table is substantially the same as that of the frame 35 A, to wit, rectangular; but it is somewhat smaller than said frame in both dimensions. The skirt is secured to said frame by screws 15 which pass through holes in the flange 14. 40 It will be seen, therefore, that the skirt provides a very substantial tie for the longitudinal and transverse members of the frame A, whereby said frame is securely held within the sheet metal covering 1. The 45 lower edge of the skirt is turned inwardly and then upwardly and back upon itself to form reinforced stiffening flanges 16 therefor.

The central part of the front portion 11 50 of the skirt of the table is cut away and the surrounding edges of the opening thus provided is turned inwardly at right angles to the plane of said portion, as shown at 17 in Fig. 4. This supplies an opening for the 55 drawer B which is of wood and of ordinary construction, and to the front piece 18 thereof is secured a rectangular sheet metal plate 19, the edges whereof are curved over the edges of the front piece 18. The plate 19 60 is secured to the piece 18 by screws 20 and a convenient "drawer-pull" 21 is attached to the central portion of the plate 19 by screws 22 which pass through holes therein and through the plate 19 into the front piece 18 65 and thereby assist in the securing of the

plate 19 to said front piece. To strengthen the long narrow piece of stock which is left along the lower edge of the front portion 11 of the skirt after the drawer opening has been made therein, I provide an angle iron 70 23 which extends some distance beyond either end of the opening and is secured to the skirt by rivets 24.

The legs 25 of the table are of tubular formation as will be seen most clearly from 75 Figs. 6 to 9 inclusive and are substantially square in cross section, and taper from top to bottom. The upper end of the leg is reinforced by a strip 26 which is riveted to the inside of the leg and its lower end is provided with an inturned flange 27 to strengthen it and for a further purpose which will be made apparent hereinafter. When attached to the table, the upper end of the leg is caused to bear firmly against 80 the underneath surface of the frame A and to fit snugly within the corner of the skirt of the table, as is shown in Fig. 6. Angle clips 28 which occupy the corners between the ends of the reinforcing flanges 16 of 85 the table skirt and the adjacent portions of the legs have their vertical branches secured to said legs in any suitable manner, as by rivets 29, and their horizontal branches are secured to the flanges 16 by bolts 30.

In Fig. 10 I have illustrated a bearing plate or tread which I provide for the lower end of the legs of the table, and which is of the same general outline as the bottom of the legs. In order to reduce the bearing portion thereof and to present a smooth and rounded surface to the floor, I make the central part of the plate 31 spherical. A hole is punched directly in the center of the plate and the metal surrounding it is countersunk as shown 100 at 32 for the reception of the conical head of the screw 33. This screw is adapted to be threaded into a hole in the anchor plate 34 which resides within the lower end of the table leg and extends thereacross, said plate 105 having downturned ends 35 which bear upon the inner side of the flange 27. To prevent the turning of the plate 31, I form lugs 36 upon two of its corners which are diametrically opposite each other, which lugs extend 110 upwardly into the lower end of the table leg and are confined within the corners thereof.

Suitable slides are provided for the drawer B by angle plates 37 which extend from the front portion 11 to the rear portion 12 of 115 the table skirt. As a convenient means of fastening said angle plates to the aforesaid portions of the skirt of the table I turn the ends of each of the flanges of said plates at right angles to the body portions thereof 120 and rivet such overturned ends to the skirt as shown at 38. The angle plates 37, besides forming suitable slides for the drawer B, assist, materially, in strengthening the skirt 125 of the table.

Having thus described my invention, what I claim is:—

1. An article of furniture comprising a substantially rectangular sheet metal top, the central portion of which is bulged upwardly and which is surrounded by a bead having a depending flange extending therearound, the lower edge whereof is turned inwardly a distance less than the width of the aforesaid bead to form a channel, longitudinal members extending along the opposite edges of the top and having their outer edges contained within said channel, transverse members spacing apart the ends of the aforesaid longitudinal members and having their outer edges contained within the aforesaid channel, a skirt for said article of furniture having a horizontal flange that is secured to the underneath surfaces of the aforesaid members whereby said members are held against relative movement, and a layer of yielding material between the adjacent surfaces of the top and the longitudinal and transverse members.
2. An article of furniture comprising a sheet metal top which is surrounded by a bead having a depending flange extending therearound, the lower edge whereof is turned inwardly a distance less than the width of the aforesaid bead to form a channel, members having their outer edges contained within said channel, and a skirt for said article of furniture having a flange that is secured to the aforesaid members whereby the said members are held in place.
3. An article of furniture comprising a sheet metal top which is surrounded by a bead having a depending flange extending therearound, the lower edge whereof is turned inwardly a distance less than the width of the aforesaid bead, members which bear against the inner edge of the bead and have their edges resting upon the inturned portion of the aforesaid flange, and a skirt for said article of furniture having a flange that is secured to the aforesaid members whereby said members are held in place with their underneath surfaces in a common plane.
4. An article of furniture comprising an enameled sheet metal top which is surrounded by a bead having a depending flange extending therearound, the lower edge whereof is turned inwardly a distance less than the width of the aforesaid bead, members which bear against the inner edge of the bead and have their edges resting upon the inturned portion of the aforesaid flange, a skirt for said article of furniture having a flange that is secured to the underneath surfaces of the aforesaid members whereby said members are held in place with their underneath surfaces in a common plane, and a layer of yielding material between the adjacent surfaces of the top and the aforesaid members.

In testimony whereof, I hereunto affix my signature in the presence of two witnesses.

GEORGE L. HARRISON.
